J. A. CONBOIE.
DROPPING BOARD CLEANER.
APPLICATION FILED MAR. 25, 1913.

1,102,005.

Patented June 30, 1914.

UNITED STATES PATENT OFFICE.

JOSEPH A. CONBOIE, OF PITTSBURG, CALIFORNIA.

DROPPING-BOARD CLEANER.

1,102,005.

Specification of Letters Patent. Patented June 30, 1914.

Application filed March 25, 1913. Serial No. 756,663.

To all whom it may concern:

Be it known that I, JOSEPH A. CONBOIE, a citizen of the United States, residing at Pittsburg, in the county of Contra Costa and State of California, have invented new and useful Improvements in Dropping-Board Cleaners, of which the following is a specification.

This invention relates to poultry apparatus and particularly to a device for cleaning the dropping board of poultry houses.

An object of the present invention is to provide a mechanism whereby the dropping boards beneath roosts in chicken houses may be rapidly, readily and thoroughly cleaned of accretions, thus eliminating hand scraping and loss of time.

The invention consists of a scraping and gathering tray with means for operating the same along the dropping board.

It also comprises details of construction which will be more fully explained by reference to the accompanying drawings, in which—

25 Figure 1 is a plan view of the device showing a portion of a dropping board. Fig. 2 is an edge view of same partly in section.

A portion of a poultry house is shown in plan at 2, along the wall of which extends 30 a horizontal dropping board 3. Above the dropping board 3 are arranged roosts 4.

Good practice requires that the dropping board be cleaned every morning and this is usually done by hand tools, requires considerable time and is annoying to laying fowls in the nests.

My invention resides in providing an apparatus consisting of one or more scoops, trays or shallow pans 5, with the front wall 40 removed and turned slightly beneath the front edge, as 6, to form a shoe which will automatically rise over the shoulders at the edges of the flooring or dropping board structure. The trays 5 are hingedly connected at 7 to a traveler or carriage with a beam 8, at the ends of which are trucks with running wheels 9 and side-thrust wheels 10 running in guides or tracks 11 arranged along the sides of the dropping board.

45 To the carriage beam is connected a cable or haul rope 12, a stretch of which extends forwardly to a drum or pulley 13 mounted adjacent to a window or aperture 14 at one end of the shed 2 and through which the 50 trays will project and tip when advanced by the carriage hauled by the cable during

the winding of the drum by its crank 15 or other means. The cable is returned from the drum over suitable guide pulleys 16 and connected to the carriage so that the carriage can be hauled rearward by reversing the operation of the drum. The carriage beam 8 has attached to it suitable springs 17 which reach forwardly and bear down upon the trays 5 for the purpose of causing a scraping action at their front edges and to prevent their lifting, as accumulations are encountered during the advance, and for breaking up the accretions on the board a series of picks or gouges 18 is secured to 70 the trays.

In operation the drum 13 is revolved and the trays hauled from the opposite end of the board 3 which is scraped clean of deposits by the front edges of the scoops or 75 trays. The scoops or trays are drawn forward until they pass through the window 14 when they tilt about the carriage and dump their loads into a suitable receptacle outside of the building. By reversing the 80 rotation of the drum 13 the cable will wind in the opposite direction and haul the carriage with its trays back. This whole operation requires but a few minutes and can be accomplished without in any way alarming 85 the fowl.

Having thus described my invention, what I claim and desire to secure by Letters Patent is—

1. In a poultry apparatus, the combination 90 with a floor having guides along its sides, of a scraping and gathering device traveling between the guides, and means for reciprocating the device over the floor said means comprising a haul and return drum, 95 a guide pulley, and a cable attached to the scraping device and rove through the pulley, and thence around the drum and to said device.

2. The combination in a poultry house, of 100 a floored surface having parallel side guides, a bar extending over said surface and contiguous thereto with its ends running in and held against vertical movement by said guides, and a scoop hinged at its rear edge 105 to the bar and its front edge resting on the floored surface, and means for reciprocating the bar back and forth over the length of the floored surface.

3. In combination with a poultry house 110 having a floor, a carriage, means for reciprocating the carriage over the floor, scrap-

ing trays hingedly connected to the carriage for gathering accretions from the floor and conveying same to and dumping them at one end of the floor, and springs secured to the carriage for yieldably pressing the scooping edges of the trays against the floor.

4. A mechanism for cleaning the dropping board of poultry houses, comprising a carriage, guides extending along the board 10 at its sides, and wheels on the carriage engaged by the guides and limited in their vertical movement thereby, a haul and return cable connected at its ends to the carriage, a pulley at one end of the board and a drum 15 at the other end over which the cable is rove and for operating the same to reciprocate the carriage, and a scraper and gathering device pivoted upon the carriage, with means for automatically pressing the edge 20 of the scraper down.

5. A poultry board cleaning device, com-

prising a carriage, means for reciprocating the carriage over the board, a scraping device hingedly connected to the carriage, and means for yieldably pressing the scraping 25 edge of said device against the board.

6. A poultry board cleaning device, comprising a carriage, means for reciprocating the carriage over the board, a scraping device hingedly connected to the carriage, 30 means for yieldably pressing the scraping edge of said device against the board, and gouges for breaking up accretions on the board.

In testimony whereof I have hereunto set 35 my hand in the presence of two subscribing witnesses.

JOSEPH A. CONBOIE.
